METAL CONTAINER

Eli Bourland, Philadelphia, Pa., assignor to Crown Can Company, Philadelphia, Pa., a corporation of Pennsylvania

Application May 19, 1937, Serial No. 143,593

4 Claims. (Cl. 220—40)

The present invention relates to a metal container and, more particularly, to a metal container of the type wherein the container cover may be locked upon the container body.

5 The principal object of the invention is to provide a metal container which is provided with an efficient locking means to secure the cover of the container upon the container body, the locking means being of such design that it will be 10 efficient in operation and may be economically 15 included in the container structure.

Numerous types of locking means have heretofore been provided to secure the cover of a metal container upon the container body, but 15 most of such locking means have projected outwardly from the wall of the container. Obviously, when the locking means projects outwardly from the container body, the skirt of the container cover will be bulged outwardly with the 20 result that a close seal will not be provided between the inner wall of the cover skirt and the underlying portion of the container body.

An important object of the invention is to provide a locking means for metal containers which 25 will not affect the seal between the container body and the container cover.

Another disadvantage of locking means for metal containers as heretofore produced has been that the locking means was of such design that 30 the container cover could not be applied to the container body unless it was first carefully positioned with respect to the locking means upon the container body, since if it were not positioned in the proper manner, the locking means on the 35 body and cover would become jammed with respect to each other.

Another object of the invention is to provide a metal container including locking means of such type that the cover may be moved into locked 40 position upon the container body from practically any position with respect to the container body, and which is also designed in such manner that no jamming can occur.

Other objects and advantages of the invention 45 will be apparent from the following specification and drawing, wherein

Figure 1 is a side elevation of the container of the present invention;

Figure 2 is a view in side elevation showing the 50 cover spaced slightly above the container body;

Figure 3 is a horizontal sectional view on the line 3—3 of Figure 2;

Figure 4 is a vertical sectional view showing the cover spaced slightly above the container 55 body; and

Figure 5 is a vertical sectional view showing the cover in locked position upon the container body.

The numeral 10 designates the body of the container and the numeral 11 indicates the container cover. The body of the container preferably has its top edge rolled inwardly as indicated in Figure 5 to form a strengthening bead 12, and a strengthening shoulder 13 is also formed about the wall of the container body at a point spaced 10 somewhat below the upper edge bead 12. The container cover 11 may have an outwardly rolled bead 14 at the lower edge of its skirt 15, and the upper portion of the skirt is preferably knurled as indicated at 16 to enable the cover to be 15 readily turned with respect to the container body.

At spaced points about the extreme upper portion of the container body 10, that is, between the strengthening shoulder 13 and the upper 20 edge bead 12, locking means generally indicated by the numeral 18 are provided. Four such locking means as indicated in Figure 3 are ordinarily sufficient, but this number may be varied as desired.

Each locking means 18 comprises an entrance pocket 20, one or more locking pockets 21 and an abutment 22. The pockets 20 and 21 are formed by forcing the metal of the container body inwardly as best shown in Figures 3 to 5, but the abutment projects outwardly from the surface of the body, the abutment 22 thus being the only portion of the locking means 18 which extends outwardly from the periphery of the container. The entrance pocket 18 extends upwardly along the side wall of the container and opens to the upper edge of the latter, one side wall 23 being inclined inwardly and downwardly, that is, toward the locking pocket 21, to serve as a guide, and its opposite wall 24 extends longitudinally of the container body. The vertical wall 24 is preferably under-cut at its lower portion as indicated at 25, the under-cut portion 25 being substantially of the same dimension longitudinally of the container as the locking pocket 21. The locking pocket 21 adjacent the under-cut portion 25 of entrance pocket 20 is spaced circumferentially from the under-cut, and if a second locking pocket 21 is provided, it will be correspondingly spaced from the first locking 50 pocket. The abutment 22 is closely adjacent the near end of the last locking pocket so that it will serve as a stop for a locking lug on the container cover seated in that pocket 21.

The container cover 11 has locking lugs 28 55

formed in its skirt 15, the locking lugs being so spaced that they may be engaged with the locking means 18 provided on the container body. The locking lugs 28 are also so spaced 5 from the top wall of the container cover 11 that when the underside of the top wall bears upon the bead 12 at the upper edge of the container body, the lugs 28 will be in horizontal alignment with the locking pockets 21. Furthermore, the locking lugs 28 are of such size that 10 when they are seated in the locking pockets 21 they will closely fit therein and thereby prevent the cover 11 from moving relative to the container body.

15 As shown in Figure 2, the upper ends of the entrance pockets 20 of the locking means 18 are of such width circumferentially of the container body that the locking lugs 28 may be readily positioned in the entrance pockets.

20 In use, as indicated in Figure 2, the cover 11 may be so positioned with respect to the container body 10 that each locking lug 28 will be above and in alignment with an entrance pocket 20 on the container body. Downward movement 25 of the cover 11 will bring each lug 28 against the lower wall of the entrance pocket 20, the lug being guided clockwise (to the left in Figure 2) toward the locking pocket 21 by the inclined wall 23 of the entrance pocket. Further rotation 30 of the cover in a clockwise direction will cause each locking lug 28 to pass into the under-cut portion 25 of the entrance pocket, and, with sufficient turning force applied to the cover, the locking lug will move over the surface of the container 35 body and into the adjacent locking pocket 21. If more than one locking pocket is provided, the cover may be turned to position the lug 28 in the last pocket, further movement in a clockwise direction then being prevented by the contact of 40 the lug with the abutment 22.

It will be noted that with the locking lug 28 seated in a locking pocket 21, the only element 45 of the structure which will in any way tend to vary the circumferential symmetry of the cover skirt 15 will be the abutment 22 and, in actual practice, this lug projects so slightly from the periphery of the container body surface that there can be no distortion of the cover such as would affect the close seal of the cover with 50 respect to the container body. It is well known that where the locking elements provided on the container body project from the wall of the latter, the cover, when in closed position upon the container body, is substantially bent or 55 distorted with respect to the container body, thereby markedly affecting the seal between the body and the cover.

It will be noted that even if the locking lugs 28 are not initially positioned in alignment with the 60 entrance pockets 20, the cover 11 may readily be moved downwardly upon the container body, since no large number of projecting surfaces are provided upon the body to hinder such movement. For example, in the present invention, the 65 locking lugs may be moved downwardly over any portion of the upper surface of the container body, and when the cover 11 is turned sufficiently in a clockwise direction, the lugs 28 will come in contact with the abutments 22, indicating to the 70 user that the cover is in locked position upon the body. It will also be noted that when the lugs 28 are positioned in the locking pockets 21, the cover cannot be jammed with respect to the container body, as is frequently the case with locking 75 structures including oppositely facing projections

on the container body and container cover, respectively.

The provision of abutments 22 to limit the movement of the container cover to locked position is most advantageous because the resistance 5 against further turning movement resulting from the contact of the lugs 28 with the abutments 22 is sufficient to advise the user that the cover is in locked position. In structures where the locking means on the container comprises 10 a series of outwardly projecting protuberances, all projecting to a like extent from the container body surface, the user has no way of knowing that the container cover is in final locked position with respect to the container, and will frequently turn the container cover past the last of the locking means. When this occurs, the cover must be turned in a reverse direction to lock it with respect to the container body.

It will be understood that the invention is not 20 limited to the details of construction shown in the drawing; also, that the phraseology employed in the specification is for the purpose of description and not of limitation.

I claim:

1. A metal container comprising a container body and a container cover, the body having a plurality of locking means spaced about its upper end, each of the locking means comprising an entrance pocket in the outer surface of the container body opening to the upper edge of the latter, a locking pocket circumferentially spaced with respect to the entrance pocket, and an abutment projecting outwardly from the surface of the container body at the side of the locking 30 pocket distant from the entrance pocket, the container cover having a plurality of inwardly projecting lugs formed on the skirt thereof, said lugs being so spaced that one will be arranged 35 for alignment with each of the locking means on the container body.

2. A metal container comprising a container body and a container cover, the body being provided with a plurality of locking means spaced about its upper end, each comprising an entrance 45 pocket in the outer surface of the container body opening to the upper edge of the latter, one side wall of the pocket being downwardly and inwardly inclined, a locking pocket circumferentially spaced from the opposite side wall of the entrance pocket and of less width longitudinally of the container body, and an abutment projecting outwardly from the wall of the container body adjacent the far side of the locking pocket, the container cover having a plurality of inwardly 50 projecting lugs formed on the skirt thereof, said lugs being so spaced that one will be arranged for alignment with each of the locking means on the container body.

3. A metal container comprising a container body and a container cover, the body being provided with a plurality of locking means spaced about its upper end, each comprising an entrance pocket in the outer surface of the container body and opening to the upper edge of the latter, one side wall of the pocket being downwardly and inwardly inclined, the opposite side of the pocket having a circumferential extension therefrom, a locking pocket circumferentially spaced from the extension of the entrance pocket and of the same 60 width longitudinally of the container body as the extension, and an abutment projecting outwardly from the surface of the container body at the side of the locking pocket distant from the entrance pocket, the container cover having a 65

plurality of inwardly projecting lugs formed on the skirt thereof, said lugs being so spaced that one will be arranged for alignment with each of the locking means on the container body.

- 5 4. A metal container comprising a container body and a container cover, the body being provided with a plurality of locking means spaced about its upper end, each comprising an entrance pocket in the outer surface of the container body and opening to the upper edge of the latter, one side wall of the pocket being downwardly and inwardly inclined, the opposite side of the

5 pocket having a circumferential extension therefrom, and a locking pocket circumferentially spaced from the extension of the entrance pocket and of the same width longitudinally of the container body as the extension, the container cover having a plurality of inwardly projecting lugs formed on the skirt thereof, said lugs being so spaced that one will be arranged for alignment with each of the locking means on the container body.

10 ELI BOURLAND.
